CLAIM

The ornamental design for reversible griddle, as shown and described.

DESCRIPTION

FIG. 1 is a top plan view of the reversible griddle;
FIG. 2 is a bottom plan view thereof;
FIG. 3 is a right side view thereof;
FIG. 4 is a left side view thereof;
FIG. 5 is a front view thereof;
FIG. 6 is a back view thereof;
FIG. 7 is an enlarged cross-sectional view taken along line 7-7 of FIG. 1; and,
FIG. 8 is a perspective view showing the front view, the left side view and the top view.
